SPRINKLER HEAD

Charles H. Ramsdell, Portland, Oreg.

Application April 6, 1946, Serial No. 660,207

3 Claims. (Cl. 299—141)

1

The present invention relates to sprinkler heads and is particularly concerned with a new and improved sprinkler nozzle for watering lawns, gardens, etc.

A primary object of the invention is to provide an improved sprinkler head of simple and rugged construction. Another object of the invention is to provide a sprinkler nozzle so designed that the water is ejected therefrom in the form of a fine spray. A particular object of the invention is to provide a sprinkler head adapted to be used as a permanent fixture in and around the edges of lawns, etc., as part of a general water distributing and sprinkling system.

Additional objects will become apparent from the following description of the invention and by reference to the accompanying drawing illustrating a preferred embodiment thereof.

In the drawing Fig. 1 is an elevational view of a sprinkler head embodying the present invention, the head being shown as connected to a supply pipe; Fig. 2 is a plan view of the sprinkler head; Fig. 3 is a cross sectional view taken along line 3—3 of Fig. 2, and Fig. 4 is a view through one of the slots in line with the bottom thereof showing a preferred form of slot design.

In the embodiment of the invention illustrated in Figs. 1 to 3, the sprinkler head comprises a recessed body member 10 having a relatively thick side wall 11 and a relatively thick end wall 12 integral with the side wall. The open end of the recessed body member 10 is provided with threads 13 for securing the sprinkler head to a supply pipe 14.

A plurality of cylindrical openings 16 are provided in the body member at the junction of the side walls 11 and end wall 12. These openings 16 define jet orifices radially spaced about the periphery of the end wall 12 and extending upwardly and outwardly through the body member. The discharge end of each of the openings 16 terminates in a radial slot 17 which may conveniently be formed by saw cuts in the edge of the body member formed by the junction of the outer surfaces of the walls 11 and the end wall 12. The slots 17 are each defined by a pair of substantially parallel side walls 21 and a sloping bottom wall 22, the latter merging at its ends respectively with the outer surface of the walls 11 and the outer surface of the end wall 12. As is more clearly shown in Fig. 3, slots 17 extend only part way through the walls of the body member 10 so that the quantity of water introduced into each of the slots is determined by the size of the openings 16 connecting the slots with the interior 55

2

of the body member 10. The opening 16 should be at least as wide as the slots 17.

In the drawing, the bottom walls 22 of slots 17 are shown as being perpendicular to the axis 5 of the cooperating openings 16 and as sloping away from the face of end wall 12 at an angle of about 45°. The exact angle of slope of the bottom of the slot is not critical and the slots may be cut in the edge of the member 10 at any 10 angle ranging, for example, from about 30° to 60° with respect to the end wall 12. While each of the openings 17 will generally be so arranged that the longitudinal axis thereof is perpendicular to the bottom wall 22 of the cooperating slot, 15 it is not essential that this relationship exist, the more important feature being that the longitudinal axis of the slot be substantially in line with the peripheral edge of the end wall 12 so that the jets issuing from the orifices of the openings 20 16 will contact the maximum wall area of the slot and thereby more thoroughly be dispersed into the form of a fine spray.

To facilitate the breaking up or dispersion of the water jets, the outer edges of each of the 25 triangular shaped slots 17 are preferably displaced slightly inwardly, for example, by means of a swaging tool, as shown at 23 in Fig. 4, so that in effect the walls 21 converge adjacent the outer surface of the body member. By providing such 30 converging surfaces at least in the path of the jets, a breaking up of the main portion of the streams issuing from openings 16 is assured by the contact thereof with the diverging end portions of the slot walls.

35 From the above description it will be seen that there has been provided in accordance with the present invention a simple, inexpensive, strong or rugged sprinkler head which is designed efficiently to disperse water or other fluid in the form 40 of a fine spray. The head is particularly adapted to be permanently set in or around the edges of lawns, etc., where because of its rugged construction it will be able to withstand the abnormal abuse likely to be inflicted thereon under such 45 conditions.

Having described the invention in what are considered to be certain preferred embodiments thereof, it is desired that it be understood that the specific details shown and described herein 50 are merely illustrative and that this invention may be carried out by other means.

What I claim is:

1. A sprinkler head comprising a recessed body member, a plurality of radially spaced slots in the outer edge of said body member formed by the

junction of the side and end thereof, said slots having sloping bottom walls, openings defining jet orifices extending through said body member to the bottom of said slots, the longitudinal axis of each of said openings being substantially in line with the edge of said body member.

2. A sprinkler comprising a recessed body member, a plurality of openings defining jet orifices disposed around the periphery of the end of said body member, the outer end of each of said openings terminating in a narrow slot having parallel side walls and a sloping bottom wall, the width of said openings being at least equal to the width of said slots.

3. A sprinkler nozzle comprising a cylindrical recessed body member including a cylindrical side wall and an integral end wall, a plurality of relatively narrow slots disposed around the circum-

ference of said end wall, each of said slots having side walls converging inwardly adjacent the top of said slot and an oblique bottom wall and orifice extending perpendicularly from the bottom of each of said slots to the interior of said casing.

CHARLES H. RAMSDELL.
